United States Patent Office

Des. 175,763
Patented Oct. 11, 1955

175,763

CARRYING DISPLAY KIT

Christy M. Del Mas, New York, N. Y., assignor to Michael P. Grace, New York, N. Y.

Application May 21, 1953, Serial No. 25,152

Term of patent 14 years

(Cl. D58—12.6)

I claim:

The ornamental design for a carrying display kit, as shown.
